DESIGN FOR A BOOK COVER

Leonard Mounteney, Chicago, Ill.

Application February 26, 1937, Serial No. 67,875

Term of patent 7 years

To all whom it may concern:

Be it known that I, Leonard Mounteney, a citizen of the United States, residing at Chicago, in the county of Cook and State of Illinois, have invented a new, original, and ornamental Design for a Book Cover, of which the following is a specification, reference being had to the accompanying drawing, forming a part thereof.

The figure is an elevational view in open position of a book cover showing my design.

I claim:

The ornamental design for a book cover, as shown.

LEONARD MOUNTENY.
